US00D960400S

(12) **United States Design Patent** (10) **Patent No.:** **US D960,400 S**
Ding (45) **Date of Patent:** **** Aug. 9, 2022**

(54) **SOLAR POWERED MOTION SENSOR
LIGHT**

(71) Applicant: **Zhijie Ding**, Shenzhen (CN)

(72) Inventor: **Zhijie Ding**, Shenzhen (CN)

(**) Term: **15 Years**

(21) Appl. No.: **29/781,459**

(22) Filed: **Apr. 30, 2021**

(51) **LOC (13) Cl.** **26-03**

(52) **U.S. Cl.**

USPC **D26/24**; D26/70

(58) **Field of Classification Search**

(57) **CLAIM**

The ornamental design for a solar powered motion sensor light, as shown and described.

DESCRIPTION

FIG. 1 is a perspective view of the solar powered motion sensor light showing my new design;

FIG. 2 is a perspective view from another angle thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the solar powered motion sensor light that form no part of the claimed design.

1 Claim, 8 Drawing Sheets
